CLAIM

The ornamental design for a fishing line spreader, as shown and described.

DESCRIPTION

FIG. 1 is a side view of a fishing line spreader showing our new design;

FIG. 2 is an opposite side view thereof;

FIG. 3 is a view of the left edge thereof;

FIG. 4 is a view of the bottom edge thereof; and,

FIG. 5 is a view of the right edge thereof, the top edge being identical thereto.

The broken line showing of environment in FIG. 2 is for illustrative purposes only and forms no part of the claimed design.

FIG. 1

FIG. 3

FIG. 4

FIG. 2

FIG. 5
